DESIGN FOR A PIN

Harry E. Cochenour, Chicago, Ill., assignor to Fraternal Field Managers' Association, Detroit,
Mich., an association

Application August 3, 1940, Serial No. 94,182

Term of patent 14 years

To all whom it may concern:

Be it known that I, Harry E. Cochenour, a citizen of the United States, residing at Chicago, in the county of Cook and State of Illinois, have invented a new, original, and ornamental Design for a Pin, of which the following is a specification, reference being had to the accompanying drawing, forming part thereof.

Fig. 1 is a front view of a pin showing my new design.

Fig. 2 is a side elevation of the design shown in Fig. 1.

I claim:

The ornamental design for a pin, substantially as shown.

HARRY E. COCHENOUR.
